VOLTAGE CONTROL

Edward J. Diebold, Palos Verdes Estates, Calif., assignor to International Rectifier Corporation, El Segundo, Calif., a corporation of California

Filed Oct. 20, 1958, Ser. No. 768,351

9 Claims. (Cl. 323—45)

This invention relates to a voltage control which utilizes a transformer, and enables a voltage to be varied over a wide range in a continuous manner as contrasted to step-style controls in which the output voltage is controlled in discontinuous, incremental steps.

An inexpensive voltage control for producing a variable A.C. output voltage that is continuously variable, as opposed to incrementally variable, has many potential applications. While such a device is of general usefulness in producing an A.C. voltage of desired magnitude in any system, a particularly suitable application exists in connection with the use of semi-conductor rectifiers. In order to utilize semi-conductor rectifiers in power installations, a good, and preferably cheap means is needed for controlling the input voltage to the rectifiers (output from the voltage control). Because at present there is no voltage control device which is economical, reliable, and which has properties suitable for use with semi-conductor rectifiers, such rectifiers have not yet been utilized to the full extent of their potential usefulness in power applications. It is well known that semi-conductor rectifiers are potentially useful in handling heavy industrial current loads. If a suitable voltage control were provided, they would be widely used for the purpose, because they avoid many of the disadvantages of other types of rectifiers.

Two previously suggested types of voltage controls for handling heavy loads, and which are potentially useful in connection with semi-conductor rectifiers, are the tap-changing transformer, and the induction regulator. These controls have major disadvantages which have kept them from being used for this application. For example, in using the tap-changing transformer it is necessary to change taps under load. Since the load is usually very heavy, the tap changing is a major problem which has made the required transformer quite expensive, and has limited its control range. The induction regulator, while being accurate and having many desirable characteristics, is very expensive, and the high expense of the device has in most cases eliminated it from consideration.

Still another suggested means for controlling voltage in connection with the use of semi-conductor rectifiers utilizes saturable reactors. The problem here is that saturable reactors have the disadvantage that the power factor of the rectifier input from the control utilizing the reactors decreases as the voltage is regulated down, which is an undesirable situation. Furthermore, these reactors and their controls are quite expensive. As a result the saturable reactor has not been generally accepted for industrial voltage control.

It is an object of this invention to provide a voltage control device which has a wide control range, a low maintenance rate, and a relatively low cost, which thereby enables semi-conductor rectifiers to be used for heavy industrial loads, and thereby secures the benefits of the inherent desirable properties of these rectifiers for commercial systems.

According to this invention, an auto-transformer is provided with a main winding and two auxiliary windings, which windings are flux-coupled. Each of the auxiliary windings is provided with switching means for either adding its voltage to that of the main winding, or for subtracting it. An induction regulator is directly coupled to one of these auxiliary windings so that the voltage output of this winding can be varied continuously.

2

By appropriate switching of the windings in blocks, and the continuous variation of voltage in the induction regulator, a smooth, continuous change of voltage is obtained.

A preferred but optional feature of the invention resides in a switching control which sequentially controls the switching of the auxiliary winding and induction regulator to accomplish a smooth step-less variation of the voltage.

The above and other features of this invention will be fully understood from the following detailed description and the accompanying drawings, of which:

FIG. 1 is a circuit drawing of a voltage control according to this invention;

FIG. 2 is a table showing the switching sequence for changing the voltage in the device illustrated in FIG. 1;

FIG. 3 is a plan view partly in block notation showing a cam and an interlock for operating the various switches;

FIGS. 4—15 are cross-sections taken at lines 4—4 through 15—15, respectively, of FIG. 3; and

FIG. 16 is a cross-section view of an induction regulator used in the circuit of FIG. 1.

FIG. 1 is a showing of the invention adapted to vary the magnitude of an A.C. voltage output. It is to be understood that this control is of general application, and can be utilized in connection with systems of more than one phase, in which event one of the controls shown would be provided for varying the magnitude of the voltage in each phase.

A main winding 10, herein called a first winding, is mounted on an iron core 11 (shown schematically in FIG. 1). A first end of this winding is connected at point 12 to a first input terminal 12a and to an output terminal 12b.

The other end of winding 10 is connected at junction 13 to a lead 14 which leads connects to a second input terminal 15 and, through switch K to a third terminal 16 which is an output terminal. A lead 18 connects to lead 14 at a junction 19. Lead 18 branches to leads 20 and 21. Leads 20 and 21 connect to a first auxiliary winding 22, herein called a second winding, which winding is wound on core 11. Depending upon switch settings, its voltage effect will either be added to or subtracted from that of winding 10. Leads 20 and 21 are joined at the ends of winding 22 to junctions 23 and 24. A switch B, herein called a first switch, is connected in lead 20 between lead 18 and junction 23. A switch C, herein called a second switch, is connected in lead 21 between lead 18 and junction 24. Leads 25 and 26 connect respectively with junctions 23 and 24 and connect with a lead 27.

A switch D, herein called a third switch, is connected in lead 26 between junction 24 and lead 27. A switch E, herein called a fourth switch, is connected in lead 25 between junction 23 and lead 27. Lead 27 connects to a junction 28, herein called a first junction, where it is connected to leads 29 and 30. Lead 29 includes a switch F, herein called a fifth switch, and lead 30 includes a switch G, herein called a sixth switch.

Lead 29 connects to junctions 31 and 32. Lead 30 connects to junction 33, herein called a second junction. Lead 29 also extends to connect to junction 34, and a switch I, herein called an eighth switch is included in lead 29 between junctions 32 and 34. A switch H, herein called a seventh switch, is connected in a lead 36, which is connected between junctions 33 and 34.

A second auxiliary winding 37, herein called a third winding, is connected between junction 31 and junction 38. It is mounted on core 11. One coil 39 of an induction regulator 39a (shown in FIG. 1) is connected between junctions 32 and 38, while the other coil 40 of the induction regulator is connected between junctions 33 and 38. Coils 39 and 40 are two windings of an induc-

tion regulator, one of which is rotatable relative to the other so as to vary the voltage controlled by this induction regulator between a negative maximum and a positive maximum, including a zero value between them. The voltage effect of this induction regulator is added to or subtracted from that of the auxiliary winding 37. The voltage of winding 37 is added to or subtracted from that of winding 10, the same as the voltage of winding 22, by appropriate switch settings.

Lead 17 interconnects junctions 34 and 41. A lead 42 taps the center, or medial point of winding 22 and connects it to lead 17. A switch J, herein called the ninth switch, is connected in the lead 42.

It is the object of the device shown in FIG. 1 for the two auxiliary windings 22 and 37 to be selectively connected relative to the winding 10 so that their voltages are either added to or subtracted from that of winding 10. It is the purpose of the induction regulator which comprises coils 39 and 40 to provide a smooth stepless variation of a voltage increment effective upon the auxiliary winding 37 so as to make small adjustments in the voltage output. The switches are connected as shown for the purpose of selectively causing the auxiliary windings 22 and 37 to either add to or subtract from the voltage of the main winding 10 in steps, and for the induction regulator to "fill in" the voltage control over the increment between each one of the steps, thereby achieving the overall effect of a step-less voltage control.

In order to provide for this voltage control, during which time the auxiliary windings 32 and 37 are variously switched in and out or reversed in their polarity relative to the winding 10, it is necessary to perform switching under load, and therefore means are provided for causing this to be done without arching so that the switches can be relatively slow moving switches which do not require special design for heavy arcing performance. The ability to use non-arching switches results in a large reduction in cost of the switches.

The switching scheme for voltage control will be explained with reference to FIG. 2. It will be understood that persons skilled in the switching art could design other switching sequences for the same purpose, but these achieve the desired results. The cams necessary for the switching device will be described following a description of the switching operations which cause the voltage to be regulated from a higher level down to a relatively lower level.

In FIG. 2, an X in a column indicates that the switch of that column is closed. The absence of an X in the column indicates that the switch is open.

The object of the device is to add or subtract the voltage effects of the auxiliary coils 22 and 37 and the induction regulator 39a to the voltage of the main transformer winding 10. The disclosure of this technique will be assisted by applying certain arbitrary numerical values to these windings. Assuming that the voltage of the main transformer winding 10 is unity, then the auxiliary winding 22 will preferably have a relative numerical voltage value of $\frac{1}{2}$ (which may be plus or minus $\frac{1}{2}$). The auxiliary winding 37 will preferably have a relative numerical voltage value of $\frac{1}{2}$ (which may be plus or minus $\frac{1}{2}$). The relative numerical voltage value of the induction regulator 39a may preferably vary from a value of $-\frac{1}{2}$ wherein its value is subtracted from that of the auxiliary winding 37 to a numerical value of $+\frac{1}{2}$ when it is added to the value of winding 37. The range from $-\frac{1}{2}$ to $+\frac{1}{2}$ in the induction regulator is continuous.

The letter A is used in FIG. 2 to indicate that, in a given range, the voltage effect of the particular winding or induction regulator is additive to that of main winding 10. The letter S indicates that it is subtractive.

The direction of change of the voltage effect of the induction regulator in the switching operation is shown by an arrow indicating whether the value goes from additive to subtractive, or the reverse thereof. With par-

ticular respect to ranges 2, 4 and 6 of the coil 40, the tendency of the induction regulator to go from subtractive to additive refers to a reversed polarity, as will be further explained below.

Now with reference to FIG. 2, the control will be described in connection with a cycle of controlling the voltage from a value of $(1+\frac{1}{2})$ to $(1-\frac{1}{2})$ of the voltage of the secondary winding.

In order that the induction regulator may be made as small as possible it is provided for it to go through one-half of its cycle in each one of six ranges. The induction regulator will therefore make three full turns in proceeding through six switching ranges.

It is to be understood that what has been shown in the way of the number of ranges, and the relationship of the induction regulator to the auxiliary winding, is merely a single example, and that persons skilled in the art could make substitutions of relative voltage values, number of windings, and the like and still obtain the benefit of this invention. Accordingly this system is merely given by way of example and not of limitation.

Now starting with range 1, which includes the highest control voltage attainable with the system shown, the auxiliary windings 22 and 37 both add their respective voltage effects to the main winding 10. At the upper end of the range, the induction regulator adds its full voltage effect. At the end of the range, after its rotatable coil is turned 180°, its voltage is subtractive. Using the numerical example given above, the voltage control effect exerted during range 1 extends from $\frac{1}{2}$ to $\frac{1}{2}$. That is, the effects of windings 22 and 37 are $\frac{1}{2}$, and the effect of the regulator drops from $+\frac{1}{2}$ to $-\frac{1}{2}$. In range 1, switches B, D, F and H are closed. Current can flow from junction 19 through switch B, through the auxiliary winding 22 in upward direction in FIG. 1, through switch D, to junction 28, from which it proceeds through switch F, through auxiliary winding 37 in an upward direction in FIG. 1, and through coil 40 to junction 33 thence through switch H to the terminal 16. It will be appreciated that at the top of range 1, the voltage effect of coil 40 was additive to that of auxiliary winding 37 while after a 180° turn, at the lower end of the range, it is subtracted.

The voltage across the induction regulator is only a small fraction of the voltage output. It can therefore be made of inexpensive, single construction, without elaborate insulation and other costly features. The control of this invention thereby achieves the continuous variation feature of an induction regulator by using a much smaller and cheaper one than is required when the induction regulator is used to vary the voltage over the whole control range of the device.

An example of a suitable induction regulator 39a is shown in FIG. 16. This regulator includes a stator 85 with interior slots 86, 87, which receive coil 40 and a rotatably mounted rotor 88 which rotates around a central axis 89. The stator slots are located oppositely to each other relative to the axis of the rotor. The rotor has a set of exterior slots 90, 91 which receive a coil 39, and also a second set of slots 92 angularly related in quadrature to slots 90 and 91, the slots 90 and 91 receiving a short-circuited single turn 93. Since the two slots 90 and 91 are located oppositely to each other on the rotor core, and the slots 92 (of which there are two) are also located oppositely to each other on the rotor core, the plane of coil 93 is angularly displaced at 90° relative to the plane of coil 39. The terminals of rotor coil 39 may be connected into the circuit of FIG. 1 by conventional means such as slip rings (not shown).

When the rotor is turned to the position where the rotor slots 90, 91 are juxtaposed with the stator slots 86, 87 respectively, as shown in FIG. 16, the rotor and the stator coils 39 and 40 respectively are tightly coupled together in the magnetic circuit formed by the stator core and the rotor core. Under this circumstance, the impedance

across coil 40 is approximately equal to the impedance across coil 39 multiplied by the turns ratio between the two coils, and accordingly the impedance of coil 40 is prevented from becoming excessively high. It will be appreciated that if the impedance of coil 40 were allowed to become unduly high, it would undesirably restrict the flow of output current through this coil to the switch H.

When the rotor is turned at 90° to the position shown in FIG. 16, the rotor and stator coils are in quadrature with each other so that there is substantially no coupling between coils 39 and 40. Under this circumstance, coil 39 has substantially no influence on coil 40; and if it were not for the presence of the short-circuited turn 93 the impedance of coil 40 would become unduly high. But in this position, the slots 92 of coil 93 are now juxtaposed with the respective slots 86 and 87 of stator coil 40. Accordingly, such current as flows through coil 40 now induces a voltage in the short-circuited turn 93, and since the impedance of the short-circuited turn is low, its effect is reflected into coil 40 to maintain the impedance of coil 40 within the desired limits. It will be recognized that in positions between that shown in FIG. 16 and the position of quadrature relative thereto, both coils 93 and 39 will have their effect in maintaining the impedance of coil 40 within a desired limit. Since coil 93 is always in quadrature with coil 39, coil 93 will never have any appreciable effect on coil 39.

It should be understood that the induction regulator per se is not the invention. It is a well known type of component needing no further discussion here. A form of induction regulator is shown and described in Pender and Del Mar, Electrical Engineers' Handbook, Electric Power, 4th edition, copyright 1949 by John Wiley & Sons, Inc., New York, N.Y., at pages 12-32 (see FIG. 17 on this page).

The above described movement of the induction regulator, in combination with the switch setting exhausts the control range 1, and it is necessary to enter range 2. Accordingly the switch settings are changed in a sequence that is denoted as switch-over 1. During this switch-over the switches are arranged so that the auxiliary winding 22 is additive, the auxiliary winding 37 is cut out, and the induction regulator is subtractive. For this purpose switches B, D, F, G, H and I are closed. The circuit beginning at junction 19 is through the switch B, auxiliary winding 22 in an upward direction, through switch D to junction 28. The switches F, G, H and I are all closed, thereby removing any potential difference across the auxiliary winding 37 and across the induction regulator. It will be observed that the numerical value of $\frac{1}{12}$, which is the voltage value of winding 22, is maintained during switch-over 1.

To carry out voltage regulation in range 2, switch H is disconnected, leaving switches B, D, G and I connected. The circuit is from junction 19 through switch B, through auxiliary winding 22 in an upward direction, through switch D to junction 28, thence to switch G to and through the induction regulator and the auxiliary winding 37 in a downward direction in FIG. 2, and thence through switch I to terminal 16.

The direction of current flow through the induction regulator and the auxiliary winding 37 is reversed from the direction of flow in range 1, so that as shown by the columns the effect of auxiliary winding 37 is subtractive and the relative (negative) polarity of the induction regulator goes from subtractive to additive. Taking the numerical example used herein, at the upper limit of range 2, auxiliary winding 22 adds its value of $\frac{1}{12}$ from which the value $\frac{1}{12}$ is subtracted by auxiliary coil 37, and the induction regulator subtracts its negative value so as to add $\frac{1}{12}$, the net effect being that the value of the upper level of the range is $\frac{1}{12}$. The value at the lower end of the range after the induction regulator has turned another half revolution is $\frac{1}{12}$, because then both winding 37 and

regulator 39a exert a negative effect opposed to the winding 22.

It is next necessary to switch over to range 3, the switch-over being carried out in three steps. During this switch-over, the auxiliary coils 22 and 37 are switched out, and the induction regulator assumes its initial additive condition. The first operation of switch-over 2 simply connects switch J in addition to the settings of the lower end of range 2. With switch J closed, the principal voltage effect is derived from the lower half of winding 22, that is, $\frac{1}{12}$. The effect of flow through G and I is negligible. The second step in switch-over 2 is to open switches D, G and I, so that the voltage effect is $\frac{1}{12}$. The third step is to close switches F and H, the voltage effect still being substantially $\frac{1}{12}$, and switch-over 2 is completed.

Thereafter to commence range 3, switch J is opened and switch D is closed. Under these circumstances the circuit from junction 19 is through switches B and E, thereby by-passing winding 22, so that it exerts no effect on the voltage of the device, thence to junction 28, through switch F and thence in an upward direction through winding 37, and through the induction regulator and switch H to terminal 16. During this range, the induction regulator goes from additive to subtractive so that the range begins with a value of $\frac{1}{12}$ on account of auxiliary winding 37 plus $\frac{1}{12}$ for the initial additive effect of the induction regulator, which equals an effective value of $\frac{1}{12}$ down to a value of zero on account of the finally subtractive effect of the inductive regulator. At this time, range 3 being exhausted, switch-over 3 is begun. Switch-over 3 is accomplished in three steps by closing switch K, herein called a tenth switch, switches B, E, F, and H remaining closed. Switch K is a substantial short circuit across the auxiliary windings and the induction regulator, so that when switch K is closed there is no substantial flow of current through any of the auxiliary windings, even though switches E, F and H are closed. The voltage effects of the windings and regulator are therefore zero. The second step of switch-over 3 comprises opening switches D, E, F and H, leaving switch K closed. This holds the voltage at zero. The third step of switch-over 3 is to close switches C, D, G and I, K remaining closed as a short-circuit. This completes switch-over 3, and range 4 can be started.

Range 4 is commenced by opening switch K. Switches C, D, G and I remain closed. By this arrangement auxiliary winding 22 is by-passed through switches C and D, and the circuit is through switches G and I. The initial effect of the induction regulator (which goes from the subtractive to the additive of a negative quantity in range 4) is to cancel out the effect of auxiliary winding 37. Rotation of the induction regulator changes its net value from $+\frac{1}{12}$ to $-\frac{1}{12}$, added to the $-\frac{1}{12}$ of winding 37, so that the upper limit of range 4 is zero, and its lower limit is $-\frac{1}{12}$. This completes range 4.

Switch-over 4 is next begun in order to enter into range 5. For this purpose switch C is opened, switches G and I remain closed and switch J is closed. The effect of this switch arrangement is that flow through switches C and J amounts to $-\frac{1}{12}$ while flow through switches G and I is not possible because switches D and E are both open. The value of the voltage is then $-\frac{1}{12}$.

The second step of switch-over 4 is to open switches G and I, leaving only switches C and J closed which, as has been seen, produces the relative numerical voltage effect $-\frac{1}{12}$.

The third step is to close switches E, F and H along with switches C and J. Switches C and J, as has been seen, produce an effect of $-\frac{1}{12}$, while the flow via switches E, F, H produces only a negligible voltage increment, the regulation value being principally established by flow through switches C and J at $-\frac{1}{12}$. At this time range 5 can be entered.

Range 5 is commenced by opening switch J, leaving switches C, E, F and H closed. This causes the effect

of winding 22 to be subtractive in the amount of $-\frac{1}{12}$. The effect of winding 37 to be additive in the amount of $+\frac{1}{12}$ and the induction regulator value goes from an additive $\frac{1}{12}$ to a subtractive $\frac{1}{12}$, thereby causing the range to extend from $-\frac{1}{12}$ to $-\frac{1}{12}$. At the end of range 5, 5 switch-over 5 is begun.

For switch-over 5, switches G and I are closed, leaving switches C, E, F and H closed. The effect of connecting switches F, G, H and I concurrently is to remove any potential from across auxiliary winding 37 and across the induction regulator, so that the entire voltage effect is due to flow through winding 22, which leaves the transition value in switch-over 5 at $-\frac{1}{12}$.

Range 6 is entered by opening switches F and H, leaving closed switches C, E, G and I, thereby rendering the effect of windings 22 and 37 subtractive, while the induction regulator goes from subtractive to additive (of a reversed, negative, polarity), thereby causing the range 6 to extend from $-\frac{1}{12}$ to $-\frac{1}{12}$.

This completes the regulatory cycle from its high value of 1.5 times some nominal voltage to .5 times the same nominal voltage. The switching sequence would be reversed in going in an upward direction, and can be stopped at any desired point in the switching cycle where the desired voltage is obtained.

A means for actuating the switches in accordance with the switching table shown in FIG. 2 is illustrated in FIG. 3. The switch-actuating device 50 is shown schematically in this figure, as is the induction regulator 39a. A first shaft 52 enters the switch-actuating device 50, which bears a first driven Geneva gear 53. A drive shaft 54 is rotatably mounted adjacent to the shaft 52 and bears a first driver Geneva gear 55. The drive shaft 54 carries a second driver Geneva gear 56. Gear 56 engages a second driven Geneva gear 57 which is mounted to a second shaft 58. The second shaft 58 rotates one of the coils of the induction regulator, preferably coil 40. The shaft 52 turns cams to be described.

Gears 56 and 57 are shown in full detail in FIG. 4. Gear 56 has a locking ring portion 59 extending around somewhat more than 180° of its periphery, and teeth 60 on the remainder of its periphery. Gear 57 has two sets of teeth 61 in like number and size as teeth 60 so as to mesh therewith. Locking grooves 62, 63 are placed between the two sets of gear teeth 61. It will be observed that each set of teeth 61 extends for a few degrees less than 180° so that the actuation of the gear 57 by teeth 60 just moves the locking rings 59 and locking grooves 63 into position such that the gear 57 is non-rotatable while the locking ring 59 engages one of the grooves 63. This holds the gear 57 against rotation for substantially half-rotation of the drive shaft 54 and turns the gear 57 by one-half revolution for every full revolution of the gear 56.

The gears 53 and 55 are shown in full detail in FIG. 5. Gear 55 bears six teeth 55a on its periphery so that teeth 55a engage corresponding teeth 64 on gear 53 once every revolution of the shaft 54. Each engagement of teeth 55a and 64 carries the gear, and therefore shaft 52, through one-sixth of one revolution. That is to say, this wheel has provisions for twelve steps. In this apparatus, because there are six ranges and five switch-overs, only eleven of these twelve steps will be utilized. The ranges are gone through when gear 53 is not rotating, and the gear 57 is, and the switch-overs are gone through while gear 53 is rotating, and gear 57 is not.

Between each set of teeth 64 there is a locking groove 65 which is adapted to be engaged by the locking ring 66 on the periphery of the gear 55.

It will now be seen that when shaft 54 is turned that for every rotation of the shaft 54, there is a 60° rotation of the gear 53 which rotation changes the switch positions, and a 180° rotation of gear 58 which turns the induction regulator coil. These movements are staggered so that when the gear 53 is moving, the gear 57 is held

still. Therefore there is an alternating movement between the gears 53 and 57 and they do not move concurrently. Thus, while the gears 53 and 55 are in the alignment shown in FIG. 5, the cams will be arranged so that the device is in one of the ranges and while the teeth 55a and 64 are engaged, the cams will be engaging in a switch-over operation. While the teeth 60 and 61 are engaged, the induction regulator is being turned (this situation being shown in FIG. 4, which is a concurrent condition with that shown in FIG. 5), and when the locking ring 59 is engaged in a locking groove 63, the gear 57 and the induction regulator are not turning.

While gear teeth 55a and 64 are engaged, the device 15 is in switch-over. When gear teeth 60 and 61 are engaged, the device is in a range. These conditions are mutually exclusive. This is because the two Geneva drives shown in FIGS. 4 and 5 operate alternately so that the induction regulator setting is not changed during the switch-over and switch-over does not occur when the induction regulator is being turned.

A schematic representation is made in FIGS. 6 to 15 showing the cam relationships in device 50. In FIGS. 6 and 7 are shown cams 70 and 71 respectively, operating 25 switches B and C. The cams are pinned to shaft 52, and have actuating segments 72, 73 respectively, which are segments relatively far from the center of rotation of shaft 52. These segments tend to close the switch. The cams have dwell sections 74 and 75 which are closer 30 to the center of the shaft 52, at which sections the switch is open, the open and closed conditions being respectively illustrated in FIGS. 7 and 8.

FIGS. 9-16 illustrate cams 76-83, which are for the purpose of actuating switches D through K respectively. 35 All of them are pinned to shaft 52.

A mechanically simple and electrically sound means for varying a voltage over an extended range is provided by this device. It will be observed that the changing of the switch settings is always done at a condition 40 such that there is no tendency to spark across any of the switches, and the voltage output of the device during switch-over remains substantially unchanged.

This invention is not to be limited by the embodiment 45 shown in the drawings and described in the description which is given by way of example and not of limitation, but only in accordance with the scope of the appended claims.

I claim:

1. A voltage control comprising a first, second and 50 third winding, said first winding being connected in shunt across a line which extends from a pair of input terminals to a pair of output terminals, said second and third windings being physically disposed in physical proximity to the first winding so as to provide an autotransformer effect with the first winding when connected thereto, and a variable induction regulator having a pair of coils in series and variably inductively related to each other, a first of which coils is connected in shunt relationship across the third winding, and switching means having the 55 selective property of connecting and disconnecting said second and third windings to and from said first winding, and of selecting the polarity of said second and third windings relative to the first winding, and switching means connecting the end of the second of said coils which is remote from the first coil, to one of said terminals, whereby the voltage output of the control is adjustably variable in response to adjustment of the switching means in connecting or disconnecting the second and third windings to the first winding, and selecting their polarities, and adjusting the inductive effect of the induction regulator.

2. A voltage control according to claim 1 in which the inductive values of the second and third windings provide voltage increments which are fractions of the voltage 70 provided by the first winding.

3. A voltage control according to claim 2 in which the relative voltage effects of the first, second and third windings are in the ratio of $1\frac{1}{12}:1\frac{1}{12}:1\frac{1}{12}$.

4. A voltage control according to claim 2 in which the maximum numerical effect of the induction regulator and of the third winding are in the ratio of 1:1.

5. A voltage control comprising: a first winding having a first and a second end; a second winding having a first and a second end; a third winding having a first and a second end; a variable induction regulator comprising a pair of relatively rotatable coils, each of said coils having a first and a second end; and ten switches, each of said switches being capable of assuming an open and a closed condition, the open condition opening the circuit through the switch, and the closed condition closing the circuit through the switch; a first end of the first winding being connected to a first terminal, the first and second of said switches being connected to a second terminal and the second end of the first winding, and to the first and second ends, respectively, of the second winding, the third and fourth of said switches each having a side connected to the second and first ends of said second winding, respectively, the sides of said third and fourth switches remote from the second winding connecting to a first junction, the fifth of said switches being connected between said first junction and the first end of said third winding, the sixth of said switches being connected between the first junction and a second junction, the first and second ends of the first coil being respectively connected to the first and second ends of the third winding, the first end of the second coil being connected to the second end of the first coil, and the second end of the second coil being connected to said second junction, the seventh switch being connected between said second junction and a third terminal, the eighth switch being connected between the first end of the first coil and said third terminal, the ninth switch being connected between a medial point of the second winding and said third terminal, and the tenth switch being connected between the second end of the first winding and the third terminal.

6. A voltage control according to claim 5 in which means are provided for turning the coils of the induction regulator relative to each other, and for sequentially actuating said switches, said switches being actuatable only when the coils are held against rotation, and the coils being rotatable only when the switches are restrained against actuation.

7. A voltage control according to claim 6 in which the said means comprise a pair of alternately operating Geneva drives.

8. A voltage control according to claim 6 in which a cam is provided for each of the switches, said cams being turned by a first shaft, a first Geneva gear on said first shaft, a drive shaft, a first driver Geneva gear on said drive shaft engaging said first driven Geneva gear, a second shaft for turning one of said coils, a second driven Geneva gear on the second shaft, and a second driver Geneva gear on the drive shaft, engaging said second driven Geneva gear, the two driver Geneva gears driving their respective driven Geneva gears at non-concurrent periods.

9. A voltage control according to claim 8 in which an individual cam is provided for each of said switches, each of said cams being adapted to open and close its respective switch, the control being actuated in six ranges, with a switch-over between each range, the cams closing and opening the respective switches in accordance with the following sequence, wherein an "x" indicates that the cam closes the switch, and a void indicates that the switch is open:

25	Switches									
	B	C	D	E	F	G	H	I	J	K
Range 1.....	x		x		x		x			
Switch-Over 1.....	x		x		x		x			
Range 2.....	x		x		x		x			
Switch-Over 2.....	x		x		x		x			
Range 3.....	x		x	x			x		x	
Switch-Over 3.....	x		x	x			x			x
Range 4.....	x	x			x		x		x	
Switch-Over 4.....	x	x			x		x		x	
Range 5.....	x		x	x			x			
Switch-Over 5.....	x		x	x	x		x	x	x	
Range 6.....	x		x		x			x
